UNITED STATES PATENT OFFICE

WARNER R. BUXTON, OF LONGMEADOW, MASSACHUSETTS

DESIGN FOR A BILL FOLD

Application filed June 5, 1930. Serial No. 35,909. Term of patent 14 years.

To all whom it may concern:

Be it known that I, WARNER R. BUXTON, a citizen of the United States, residing at Longmeadow, in the county of Hampden and State of Massachusetts, have invented a new, original, and ornamental Design for Bill Folds, of which the following is a specification, reference being had to the accompanying drawing, forming part thereof.

Fig. 1 is a front elevational view showing

a bill fold embodying my new design; and Fig. 2 is an end elevational view thereof.

The design appears wholly on the front face of the bill fold, shown in Fig. 1,—the back side being plain.

I claim:

The ornamental design for a bill fold substantially as shown and described.

WARNER R. BUXTON.
